UNITED STATES PATENT OFFICE.

GEORGE B. THOMAS, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

ELECTRIC SWITCH.

Application filed November 4, 1924. Serial No. 747,807.

My invention relates to electric switches, and particularly to snap switches. The object of my invention is to provide a simple and efficient mechanism of the push bar type, by which a snap make-and-break action is effected.

In the accompanying drawings—

Fig. 1 is a section on the line 1—1, Fig. 3, of an electric lamp socket provided with a switch in which my invention is embodied in one form;

Fig. 2 is a similar view showing the switch mechanism in different position;

Fig. 3 is a section on the line 3—3, Fig. 1; and

Fig. 4 is a perspective of the push bar unit.

The present mechanism is suitable for use in switches of various types, and it will be understood that its illustration in an electric lamp socket is merely indicative of one of the various types of appliances to which the invention is readily adaptable.

The insulating members of the socket comprise a button 5 of porcelain or the like and a cooperating disk 6 of fiber, paper or the like, which lies against one end of the button 5. The usual center and shell socket terminals 7 and 8 respectively, rest against the disk 6. The center terminal 7 is secured in position by the rivet 9 and has integral therewith a switch contact arm 10 which passes through the disk into the switch chamber 11 formed by a recess in the button 5. The base flange of the shell terminal 8 is in direct electrical connection with the binding screw terminal 12 through the offset extension 13 thereof, which is tapped and engaged by one of the screw bolts 14 passing through the button 5 and disk 6, in a manner well understood in the art. The other screw bolt 15 similarly passes through the button 5 and disk 6 and engages the nut 16 which overlies the base flange of the shell 8 at a point diametrically opposite the screw 14.

The second switch contact 17 is integral with the wire terminal 18 which, like the socket terminal 7, is riveted to the disk 6. The two switch contacts 10 and 17 are spaced apart in the same plane and rest against one of the opposite side walls of the switch chamber.

To make and break connection between the contacts 10 and 17, rocking levers 19 are pivoted at 20 and 21 in upper and lower

flanges 22 and 23 integral with the push plate 24, which reciprocates across the switch chamber 11 in a plane normal to the plane of the contacts 10 and 17. The levers 19 lie on opposite sides of the push plate, and their free ends are constantly urged toward each other and toward the push plate by the pull spring 25 connected to the lever ends. To accommodate and permit the play of the spring 25, the push plate 24 is centrally apertured at 26.

Any suitable means may be employed for guiding and reciprocating the push bar. Guide channels 27 and 28 formed in the button 5, and in which the push bar works, serve as guides therefor. Conventional buttons 29 and 30 of insulating material, secured at opposite ends of the push plate, extend sufficiently beyond the button 5, and socket casing (not shown), to permit manual operation of the push plate. The latter is held against angular play, in its own plane, by the disk 6, the sliding engagement with which by the lugs 31 and 32 maintains the plate at the bottom of the guide slots 27 and 28. The longitudinal play of the push plate is limited by the bays 33 and 34 against the bottoms of which the push buttons 29 and 30 bear in the opposite extreme operating positions.

Spaced from the contacts 10 and 17 and opposed thereto are walls 35 and 36 of the switch chamber, against which, in the "off" position of the switch, the rocking levers 19 lie. The throw of the switch levers is thus confined between the contacts 10 and 17 on the one hand, and the abutment walls 35 and 36 of the switch chamber on the other hand.

The operation of the mechanism is readily understood. In Fig. 1 the switch is shown in closed position, the current passing from the switch contact 17 of the wire terminal 18 through the rocking levers 19 and flanges 22 and 23 of the push plate, to the switch contact 10 integral with the center terminal 7 of the socket. On the displacement of the push plate 24 to the right (Fig. 1), the free ends of switch levers 19, held in sliding engagement with the contacts 10 and 17 by the spring 25, are forced outward and thus spread apart, thereby stretching and increasing the stress on the spring. As the axes 20 and 21 of the switch levers 19 cross the plane into which the switch levers are thus forced,

the effort of the spring causes the levers 19 to swing simultaneously on their axes toward the abutment walls 35 and 36 of the switch chamber, thus parting from the contacts 10 5 and 17 and opening the switch. A reversal of the operation repeats the movement, but in opposite direction, and again closes the switch.

The particular construction of the parts 10 may be variously modified without departing from my invention. I have shown the switch levers 19 formed of wire, bent to U-shape with offset spring anchorage 37 at their free ends, but it will be readily understood 15 that these arms may be struck from sheet metal or formed in some other fashion. I have also shown the pivot flanges 22 and 23 formed integral with the sheet metal push plate from which they are offset, but various 20 other constructions are available. It will of course be obvious that if desired the switch contacts may be so arranged as to be spanned by only one of the switch levers—in which event the others will serve merely as part of 25 the operating mechanism. These and other details of construction may be modified in many ways without departing from what I claim as my invention.

I claim—

30 1. An electric switch comprising a reciprocating centrally apertured punched metal push plate, a pair of switch levers pivoted to the plate at opposite sides of the aperture punched therein and extending on opposite 35 sides of the plate, a pull spring passing with clearance through the aperture in said push plate and uniting the lever arms, together with fixed abutments between which the free ends of the levers play and by which they 40 are detained during the rectilinear displacement of the push plate to shift the pivoted ends of the levers across the plane of the spring.

2. In an electric switch mechanism, a reciprocating push plate having upper and 45 lower bearings, and being apertured between said bearings, switch levers pivoted on said bearings and extending on opposite sides of the push plate, together with a pull spring passing with clearance through the aperture 50 in the push plate and engaging both of said levers.

3. In an electric switch, an insulating base recessed to afford a switch chamber and a guideway intersecting the latter, a push 55 plate reciprocating in said guideway, a pair of switch contacts arranged in said chamber in a plane substantially at right angles to the plane of said guideway, a pair of levers pivoted to said push plate and extending on 60 opposite sides thereof, a pull spring uniting the free ends of said levers, said push plate upon actuation serving to shift the pivotal axes of the levers across the plane of said spring to cause the throw of said levers into 65 circuit-making or -breaking position with respect to the contacts.

4. As an element of an electric switch mechanism, a sheet metal push plate having bearing flanges offset from its upper and 70 lower margins, the body of the plate between said flanges being apertured to accommodate a transversely extending spring.

5. As an assembly unit for an electric switch, a sheet metal push plate having bearing flanges offset from its opposite margins and apertured between said flanges, a pair 75 of switch levers pivoted in said flanges and extending on opposite sides of the plate, together with a pull spring extending transversely through the aperture in the plate 80 and anchored at its opposite ends to the switch levers.

In testimony whereof I have signed my name to this specification.

GEORGE B. THOMAS.
